UNITED STATES PATENT OFFICE.

EVERETT C. KLINE, OF NORWOOD, OHIO, ASSIGNOR TO THE VICTOR SAFE & LOCK COMPANY, OF CINCINNATI, OHIO. A CORPORATION OF OHIO.

VAULT CONSTRUCTION.

1,205,455.

Specification of Letters Patent. Patented Nov. 21, 1916.

Application filed March 7, 1916. Serial No. 82,551.

To all whom it may concern:

Be it known that I, EVERETT C. KLINE, a citizen of the United States, residing at Norwood, in the county of Hamilton and State 5 of Ohio, have invented certain new and useful Improvements in Vault Construction, of which the following is a specification.

My invention relates to a construction of the door securing devices for bank vaults 10 and the like, whereby the same may be opened from the inside.

Vault doors commonly are securely held in position against their seats, when locked, by what is known as the pressure system, 15 whereby pressure bars carried by the outer face of the door exert pressure by means of cams or otherwise against the face of the door jamb, and in none of the vaults now using the pressure system is it possible for 20 a person imprisoned within the vault to release himself.

My invention modifies the existing constructions in a simple manner, to permit a person within the vault to open the lock, 25 throw the bolts to the unlocked position, and remove the pressure devices from their locked position.

The advantages of the above are obvious in view of the fact that officials of banks are 30 frequently locked within the vault, either by burglars or by accident.

My invention consists essentially in carrying a shaft, whereby the pressure system can be rotated into unlocked position, entirely through the door and so constructing 35 the same at its inner end that it can be rotated by a suitable tool; also in providing the actuating device for the bolt-work with a squared socket on the inner side of the door, or other part adapted to be engaged 40 and turned by a suitable tool. The cashier, or other official, may be provided with a suitable tool or tools, preferably an implement comprising a screw-driver, whereby 45 the lock may be opened and removed from locking position, a square or angular shank for throwing the bolts to unlocked position, and a socket for engaging and turning the shaft of the pressure system.

In order that a clearer understanding of 50 my invention may be had, attention is hereby directed to the accompanying drawings forming part of this application and illustrating certain embodiments of my invention.

In the drawings Figure 1 represents an inside face view of a vault door, Fig. 2 is a vertical cross-section of the same, taken on line 2-2 of Fig. 1, Fig. 3 is an enlarged detail of the locking and bolt-actuating mechanism, Fig. 4 is a side elevation of a suitable tool for enabling a person imprisoned in the vault to unlock the door, Fig. 5 is an end view of the same, partly shown in section, and Fig. 6 is an outside face view of the 65 door.

Referring to the drawings, I have illustrated a door in which the bolt-work is operated by means of carrying-bars in the well-known manner. It is to be understood that 70 my invention is not limited to such a door, however, as it may be applied equally well to doors having other forms of bolt-operating mechanism, such as doors having what is known as geared bolt-work.

In the drawings, the door 1 is provided with horizontal bolts 2 secured to the carrying bars 3, 3' and slidably mounted in frame-members 4. The vertical bolts 5, 5' are secured to carrying-bars 6, 6', respectively, 80 and are slidably mounted in transverse frame-members 7 and 8. The lock, which may be of usual construction, is contained within a casing 9, secured on the inner face of the door 1, and having a cover plate 10. 85 The lock may comprise the usual notched tumblers, of which one is shown at 11, the pivoted drop bolt 12 and the locking bolt 13, which is adapted to extend between the dogs 14 which are pivoted at 15, 15 to the door 90 and also connected by the pin and slot connections 16, 17 to the carrying-bar 3. The tumblers 11 are mounted on shaft 11', carrying knob 11² at the front of the door in the usual manner. The carrying-bar may be 95 moved, when the lock is set for sliding the bolts, by means of the handle 18 mounted on spindle 19 journaled in the door having an arm 20 thereon which is connected by a pin and slot connection 21, 22 with the carrying-bar 3. The inner end of spindle 19 is provided with a squared socket 23, accessible from the inner side of the door.

The pressure system is operated by a shaft 24 carrying hand-wheel 25, constituting a hand-lever means, at the front of the door. Shaft 24 is connected to rotate vertical shaft 26, shaft 24 usually rotating shaft 26 by means of a worm gear connection (not shown) contained in the casing 27 116

secured to the front of door 1. The upper and lower ends of vertical shaft 26 enter housings 28 and 28', secured to the front of the door, in which they are connected to 5 rotate horizontal shafts 29, 29' usually by means of bevel gear connections 29². Shafts 29, 29', by their rotation in one direction, apply the pressure devices for holding the locked door tightly against its seat, and by 10 their rotation in the other direction, remove the pressure devices. This mechanism, of a well known character, is illustrated in Fig. 6. As shown, shafts 29 and 29' extend through bearings 41 adjacent 15 the opposite side edges of the door and carry cams or eccentric pins at their outer ends which are adapted to press against the front faces of the door jambs, or portions of the frame of the vault adjacent to the 20 door opening. As illustrated, eccentric pins 42 at the ends of shafts 29, 29' are adapted to enter openings 43 in the lugs 44, 44, mounted on the jamb, when the shafts 29, 29' are in proper angular position to aline 25 pins 42 with openings 43. Lugs 44 are provided with undercut recesses, with which the eccentric pins coact, when located therein, the rotation of hand-wheel 25 in such case serving to press the door tightly against 30 its seat.

The actuating shaft 24 of the pressure system extends entirely through door 1, in accordance with my invention, and is provided at its inner end with a squared or angular shank 24'. The portion of the frame with which the bolts coact to lock the door is indicated at 30. The vertical bolts 5 and 5' may be operated from the horizontal bolts 2 in any usual manner as by means of 40 the pivoted bell-crank connections 31, 31.

A convenient tool for opening the door from the inside is indicated in Figs. 4 and 5 in which a bar 32 is illustrated carrying a screw-driver 33 at one end and a squared shank 34 at the other, which is adapted to be inserted in the squared socket 23 of the bolt-actuating device. A second bar 35 is conveniently secured to bar 32, bar 35 having an enlarged head 36 through which bar 32 extends and to which it is secured. Bar 35 is provided with an enlarged head 37 at the other end within which is formed a squared socket 38 adapted to fit over the squared shank 24' of the worm shaft or actuating shaft of the pressure system.

If it is desired or becomes necessary to open the vault door from the inside, the person imprisoned first applies the screw driver 33 to the three knurled thumb-screws 39, to remove the outer cover 10 from the lock. Upon the removal of cover 10, the screw-driver is applied to the thumb-screw

40 which holds the dog or drop bolt 12. Upon the removal of this thumb-screw, the drop bolt 12 is slid out of position. The 65 lock bolt 13 of the lock is then slid back from between the fingers or dogs 14 of carrying bar 3, so that the carrying bar and bolts are free to be moved to unlocked position. The square end 34 of the wrench or 70 implement is then inserted in the squared socket 23 of the actuating device 20 and is given a turn to throw the carrying-bar 3 and the bolt-work to the unlocked position. The socket end 38 of the wrench is then 75 applied to the squared shank 24' of the actuating shaft 24 of the pressure system. Rotation of the wrench in the proper direction serves to rotate shafts 29, 29' to entirely remove pressure from the door, so 80 that the same can now be opened from the inside.

Having now described my invention, what I claim as new therein and desire to secure by Letters Patent is as follows:—

1. In vault construction, the combination of a door, locking means therefor, a shaft extending entirely through the door and having a hand lever means at the outer end thereof and a portion extending from the inner end thereof, adapted to be engaged by a suitable implement from the inner side of the door, to turn the same, shafting on the outer side of the door rotated in one direction or the other by the rotation of 95 said shaft, and pressure exerting means adapted to be applied to or removed from the door jamb by the rotation of said shafting and adapted to press the door firmly against its seat, substantially as set forth. 100

2. In vault construction, the combination of a door, bolt-work for securing the same, lock means for the bolt-work, on the inner side of the door, means for pressing the door firmly against its seat, means for actuating 105 the bolt-work when unlocked, comprising a shaft extending through the door having a recess of angular section in the inner end thereof, and means for actuating the door-pressing means including a shaft extending 110 entirely through the door, having a manually operable device at the outer end thereof and a portion of angular section at the inner end thereof, said recess and the angular portion of said last-named shaft being accessible from the inner side of the door, substantially as set forth. 115

This specification signed and witnessed this 2nd day of March, 1916.

EVERETT C. KLINE.
